UNITED STATES PATENT OFFICE.

GEORGE B. AMBLER, OF LEOMINSTER, MASSACHUSETTS, ASSIGNOR TO F. A. WHITNEY
CARRIAGE COMPANY, OF LEOMINSTER, MASSACHUSETTS, A CORPORATION OF
MASSACHUSETTS.

AUTOMATIC STOP FOR LOOMS.

Application filed February 10, 1922. Serial No. 535,474.

To all whom it may concern:

Be it known that I, GEORGE B. AMBLER, a citizen of the United States, and a resident of Leominster, county of Worcester, and State of Massachusetts, have invented an Improvement in Automatic Stops for Looms, of which the following description, in connection with the accompanying drawings, is a specification, like characters on the drawings representing like parts.

This invention relates to a knock-off or automatic stop mechanism which is adapted to stop the action of a loom when the filling or weft is not properly supplied. As an example of my invention I have here shown a construction designed for a loom adapted to weave a relatively stiff material such as cane or reed to make a fabric adapted for use in the construction of basketware.

The invention will be readily understood by reference to the following description of such an illustrative embodiment thereof taken in connection with the accompanying drawings, wherein:

Fig. 1 is a side elevation of the knock-off mechanism shown in connection with certain cooperating elements of the loom proper;

Fig. 2 is an end elevation as seen from the right of Fig. 1; and

Fig. 3 is a view similar to Fig. 1 showing the parts in another position.

Referring to the drawings, I have there indicated the means by which power may be applied to drive the loom by showing the shaft 5 adapted to operate the clutch or shipper or like mechanism and which may be rocked by the hand lever 7. My invention relates to means for automatically operating this shaft when the supply of filling is exhausted or when the filling breaks. For this purpose a lever 9 may be mounted on the shaft 5 which is adapted to be engaged by a shoulder 11 on a rod 13 which is power driven and herein is oscillated at each pick of the loom by means of the bell crank lever 15 operated by a cam 17 on any suitable shaft of the loom. In the present instance the shaft shown makes one revolution for each two picks and the cam therefore has two sharp rises and the lever is reciprocated on each pick of the loom after the filling has been inserted and during the action of beating up the same. If the rod

13 were controlled wholly by the cam 17 it would reciprocate substantially in a vertical line and the shoulder 11 would make contact with the lever 9 disconnecting the power from the loom. I provide suitable means whereby this disconnecting action is controlled by the filling as it is beaten up in such manner that the power is disconnected only when the filling is not present.

Referring to Fig. 1, I have there shown a strand of filling *f* as it is passed through the shed by the picking means and ready to be beaten up and I here illustrate a reed consisting of a plurality of hook-like dents 19 adapted to project up between the strands of the warp and oscillating on the rock shaft 70 beneath the plane of weave. The dents swing from the position shown in Fig. 1 to the position shown in Fig. 3 and thus beat up the filling strand towards the right in these figures. To govern the knock-off means I utilize an element adapted to be actuated by the filling itself and I herein show a fork 23 mounted on the sleeve 25 pivoted on the stud shaft 27 below the plane of weave and having tines projecting up into the path of the beaten up filling. Also carried by the sleeve 25 is a lever arm 29 which may have a pin and slot connection with the upper end of the rod 13 as illustrated in Figs. 1 and 3. It will be seen by Fig. 1 that the fork 23 and the arm 29 constitute essentially a bell crank pivoted at 27. A suitable spring 31 connected to the arm 29 normally holds the fork in the position shown in Fig. 1. If the filling *f* is in proper position the dents 19 beating up the same will rock the fork 23 clockwise viewing Fig. 1 and swing the arm 29 against the action of the spring to the position shown in Fig. 3 and will throw the upper end of the rod 13 to the left in that figure and thus move the shoulder 11 away from the lever 9. As the arm of the bell crank 15 (see Fig. 3) passes the rise of the cam, therefore, and the rod 13 is drawn downward, the shoulder 11 will not engage the lever 9, the clutch will not be thrown out and the loom will continue in operation. Should, however, the filling *f* be missing, the fork 23 will not be operated but will remain in the position shown in Fig. 1, the rod 13 will move to the dotted line position in that figure, the shaft 5 will be

rocked by means of the lever 9 and the loom will be stopped.

5 A push rod 33 shown in Fig. 1 permits the bell crank mechanism to be rocked by hand if desired.

10 In applying the invention to a loom for weaving stiff material wherein the filling is drawn through the shed the fork 23 is preferably installed at the side of the loom 15 from which the filling is drawn. In weaving with natural reed or cane, for example, the loom is frequently supplied from short pieces and if one of these is not of sufficient length to extend entirely across the fabric 20 the stop means will operate and permit the operator to correct what would otherwise be a partial misspick in the fabric.

25 Having thus described in detail the particular embodiment of my invention shown 20 by way of example in the accompanying drawings, what I claim as new and desire to secure by Letters Patent I shall express in the following claims.

Claims:

25 1. In a loom in combination with a lever controlling the application of power to the loom, a rod having a shoulder to engage the lever, means for reciprocating the rod and means to swing the rod thereby to move the shoulder away from the lever comprising an element in the path of the beaten up filling.

30 2. In a loom in combination with a lever controlling the application of power to the loom, a rod having a shoulder to engage the lever, means for reciprocating the rod, and bell crank mechanism for swinging the

35 rod thereby to move the shoulder away from the lever said mechanism comprising an arm engaging the rod and an arm in the path of the beaten up filling.

40 3. In a loom in combination with the oscillating hoop-like beat-up dents, the filling fork projecting between the pivots and the ends of the dents, a power driven member 45 having a portion to cooperate with a clutch lever, said member being connected to the fork to be moved thereby.

4. In a loom in combination with a lever controlling the application of power to the 50 loom, a driven member having a portion adapted to engage with said lever to throw the same, an element presented to the space between the dents of the reed and adapted to pass between the same, said device being 55 displaceable by the filling as it is beaten up and supported by said dents and by its displacement serving to shift said member from its normal path.

5. In a loom in combination with a lever controlling the application of power to the 60 loom, a driven member having a portion adapted to engage with said lever to throw the same and disposed out of the path of the reed, an element extending through the 65 reed from the rear and having a portion adapted to be displaced by the filling as it is pushed forward by the dents of the reed, said element connected to said driven member to position the same relatively to said 70 lever.

In testimony whereof, I have signed my name to this specification.

GEORGE B. AMBLER.

Certificate of Correction.

It is hereby certified that in Letters Patent No. 1,570,454, granted January 19, 1926, upon the application of George B. Ambler, of Leominster, Massachusetts, for an improvement in "Automatic Stops for Looms," an error appears in the printed specification requiring correction as follows: Page 2, line 43, claim 3, for the compound word "hoop-like" read *hook-like*; and that the said Letters Patent should be read with this correction therein that the same may conform to the record of the case in the Patent Office.

Signed and sealed this 23d day of February, A. D. 1926.

[SEAL.]

WM. A. KINNAN,
Acting Commissioner of Patents.
